(57) **CLAIM**

The ornamental bottle, as shown and described.

DESCRIPTION

FIG. 1 is a top, rear, and right side perspective view of a bottle;

FIG. 2 is a right side elevational view thereof;

FIG. 3 is a front elevational view thereof;

FIG. 4 is a rear elevational view thereof; and,

FIG. 5 is a top plan view thereof.

The broken lines shown in the drawing views are included for the purpose of showing environmental structure that forms no part of the claimed design.
